UNITED STATES PATENT OFFICE

LEON M. SHLENKER, OF ST. LOUIS, MISSOURI, ASSIGNOR TO INTERNATIONAL HARVEST HAT CO., OF ST. LOUIS, MISSOURI, A CORPORATION OF MISSOURI

INSECT-GUARD ATTACHMENT FOR HATS

Application filed March 24, 1930. Serial No. 433,583.

This invention relates to an insect guard attachment designed primarily for use in connection with hats of the sombrero type, more especially for hats of such type when constructed of bendable rims, such as soft straw, but it is to be understood that a guard attachment, in accordance with this invention, may be employed in connection with any style of hat, or head covering to which the guard can be secured, and the invention has for its object to provide, in a manner as hereinafter set forth, a guard for connection to the brim of a hat in depending relation with respect thereto and in a manner to surround the face, sides and back of the head and neck of the wearer to act as a protection against bites or stings of insects, but without, when in its protective position, impairing to a material extent the vision of the wearer.

Further objects of the invention are to provide, in a manner as hereinafter set forth, an insect guard for hats which is simple in its construction and arrangement, durable, thoroughly efficient in its use, readily attached to the brim of a hat, conveniently secured at its lower end in abutting position with respect to the wearer, of a size to be arranged a substantial distance from the face, sides, back of the head and the neck of the wearer, and inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is an elevation of a sombrero showing the adaptation therewith of an insect guard attachment in accordance with this invention.

Figure 2 is a vertical sectional view of the insect guard attachment showing the same

attached to a hat and in protecting position with respect to the head of a wearer.

Referring to the drawings in detail, 1 denotes the crown and 2 the brim of a hat of the sombrero type. The body of the hat is formed of a material which will permit of the brim being bent to extend downwardly. Preferably the material would be soft straw. The brim 2 has its outer marginal portion bent upon the outer face of the brim to form an inwardly extending fold 3 to provide a reinforced edge 4. The bend formed by the fold 3 provides the edge 4. A row of stitching 5 is provided for fixedly securing the fold or bent over portion 3 to the body of the rim. The row of stitching 5 is also provided for securing the guard, to be presently referred to, in depending relation with respect to the lower face of the brim 2.

The guard, referred to generally at 6, is formed from freely flexible fabric of the net type, such as mosquito netting, and with the interstices 7 formed between the threads 8 of a size to prevent the passage of the insects therethrough. The guard 6 is of annular form and gradually decreases in diameter from its upper to its lower end. The upper end of the guard corresponds in diameter to the greatest diameter of the brim 2 when the latter is in the position shown in Figure 2. The length of the guard is such that when in position it will be greater than the distance between the outer edge of the brim 2, and the shoulders of the wearer when the hat is worn.

The lower end of the guard 6 is hemmed as at 9. Extending through the hem 9 and projecting from the lower end of guard 6 is a shirring string 10 employed for detachably securing the lower end of the guard in an encompassing position with respect to the neck, collar of the shirt or the collar of the coat of the wearer. When the lower end of the guard 6 is secured in position as stated it is gathered by the string 10 whereby such end will be tightly positioned against the wearer to prevent the entrance of insects into the guard. The ends of the shirring string 10 are knotted together as at 11 for detachably holding the lower end of the guard in the position to which it has been adjusted.

The upper end of the guard is against its inner face to provide an inwardly extending fold indicated at 12, which is positioned against the lower face of the brim 2. Preferably the fold 12 will be arranged against the outer marginal portion thereof and the bend provided by the fold flush with the outer edge 4 of the brim. The body of the guard and the fold 12 are secured together and to the brim 2 by the row of stitching 5, and the latter secures the fold 3 to the body of the brim, the fold 12 to the body of the guard and secures the fold, brim and guard together.

When the guard is in protecting position, it encompasses and completely encloses in spaced relation the face, sides and back of the head and neck of the wearer, thereby protecting the wearer from bites or stings of insects. The guard 6 when used does not to any extent materially interfere with the vision of the wearer.

It is thought that the many advantages of an insect guard attachment for use in connection with hats and in accordance with this invention can be readily understood, and although the preferred embodiment of the invention is as illustrated and described, it is to be understood that changes in the details of construction can be had which fall within the scope of the invention as claimed.

What I claim is:

1. In combination a hat brim folded upon itself to form an inwardly extending fold to provide a reinforced edge, an annular guard of net-like material gradually decreasing in diameter from its upper to its lower end, said guard having its upper end bent upon itself to provide an inwardly extending fold, means common to said folds for securing the fold of the brim to the body of the latter, the fold of the guard to the body of the latter, and the body of the brim and body of the guard together, the bend provided by the fold of the guard being flush with the bend provided by the fold of the brim, said guard having its lower portion bent upon itself and secured together to provide a hem, and a shirring string positioned within and extending from said hem.

2. In combination a hat brim having its outer marginal portion bent upon the outer face of the body of the brim to form an inwardly extending fold to provide a reinforced outer edge, an annular guard of net-like material gradually decreasing in diameter from its upper to its lower end, said guard having its upper end bent inwardly upon its inner face to provide an inwardly extending fold, said fold positioned against the lower face of the body of the brim, means common to said fold for securing the fold of the brim to the body of the latter, the fold of the guard to the body of the latter and the body of the brim and body of the guard together, the bend provided by the fold of the brim being flush with

the bend provided by the fold of the guard, said guard having its lower portion bent upon itself and secured together to provide a hem, and a shirring string positioned within and projecting from said hem.

3. In combination, a hat brim having its outer marginal portion bent upon the outer face of the brim body to provide an inwardly extending fold and a reinforced outer edge, an annular guard of net-like material, open at each end and gradually decreasing in diameter from its upper to its lower end, said guard having its upper end bent upon its inner face to provide an inwardly extending fold positioned against the lower face of the brim body, means common to said folds for securing one to the brim body and the other to the guard body and for securing the latter to the brim body, said guard having an inherent part thereof providing a hem at its lower end, and a shirring string arranged within and projecting from the hem.

In testimony whereof, I affix my signature hereto.

LEON M. SHLENKER.
